Primary Examiner — Mimosa De(74) *Attorney, Agent, or Firm* — Brinks, Gilson & Lione, PC(57) **CLAIM**

We claim the ornamental design for a chair, as shown and described.

DESCRIPTION

FIG. 1 is a top upper perspective view of a chair;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof;

FIG. 7 is a left side elevation view thereof; and,

FIG. 8 is a rear lower perspective view thereof.

The ornamental design which is claimed is shown in solid lines in the drawings.
